Application September 19, 1932, Serial No. 633,799

18 Claims. (Cl. 153—35)

This invention relates to a stretching machine and method of operating the same, and is particularly intended for the stretching of long slender metal articles. It is herein described as particularly applied to the stretching of sucker rods.

In the copending application of Samuel F. Keener, Serial No. 633,778, filed September 19, 1932, there is described and claimed a process of heat treating metal articles such as sucker rods wherein the rods, after quenching and drawing, are engaged near their ends and subjected to a stretching action. The machine which constitutes the subject matter of this application is particularly valuable in carrying out the process of the above-mentioned Keener application, although it is susceptible of other uses.

In the stretching of sucker rods or the like it is desirable to permanently elongate or stretch the rods in a definite amount. This cannot be done simply by placing the rods in the grip of engaging means and moving such engaging means to a predetermined distance apart. The rods, although of the same nominal length, will vary somewhat in actual length, and this, coupled with the fact that they are sometimes slightly crooked because of the quenching step, means that there will be a varying amount of slack to be taken up between the engaging means and the rods before stretching actually commences. It is therefore important to effect a definite predetermined amount of movement of the engaging means one from the other after the slack has been taken up. In the Keener process it is contemplated that the rods will be supplied hot to the stretching machine and they may or may not be held taut while cooling. Where it is desired to hold the rods under tension while giving them an opportunity to cool, it becomes necessary to define the amount of stretching movement as above described and then to hold the rod under suitable tension while the temperature of the rod is reduced either by natural or artificial cooling. As the rod cools it contracts, and it is important to allow for such contraction while maintaining the desired tension.

These considerations make it preferable to employ fluid means, such as a hydraulic cylinder, for effecting the stretching movement. I provide for controlling the supply of fluid to the hydraulic cylinder in such fashion that there is first supplied fluid under sufficient pressure to cause stretching, and then after the stretching movement has been effected the pressure

is reduced so as to hold the rod under tension, but without further stretching, until it is ready to be released.

In the accompanying drawings illustrating a present preferred embodiment of my invention and a modification thereof,

Figures 1, 1a, 1b and 1c illustrate in a diagrammatic manner respectively a heating furnace, a quench tank, a draw furnace, and a stretching machine which may be used in carrying out the Keener process;

Figure 2 is a top plan view of the machine partly broken away;

Figure 3 is a view partly in side elevation and partly in section on the line III—III of Figure 2;

Figure 4 is a transverse section on the line IV—IV of Figure 2;

Figures 5 and 6 are detail views showing the gripping dies for engaging the rods, and associated mechanism;

Figure 7 is a diagrammatic view illustrating the control mechanism;

Figure 8 is a vertical section through one of the control valves employed;

Figure 9 is a section at right angles to the plane of Figure 8 and taken on the line IX—IX of Figure 8; and

Figure 10 is a view corresponding to Figure 7 but showing a modified form of control mechanism.

Referring to Figures 1 through 1c there is shown a heating furnace 2 which is supplied from a rack 3 with sucker rods 5 to be heat treated. When the rods have been brought up to suitable temperature they are taken out of the furnace through an opening 4 and thence supplied to notches 5 in a series of arms 6 on a rock shaft 7 in a quench tank 8. The rods are held in the bottom of the notches 5 by fingers 9, and while so held are lowered into the quenching bath. The movement of the fingers 9 relative to the arms 6 is limited by adjustable stops 9b. This construction permits of the fingers constraining the rods against major distortions, while eliminating the possibility of marring them. Of course, if desired, the stops 9b may be adjusted so the fingers will actually clamp the rod, but generally this will not be required. The constraint does not entirely eliminate warping of the rods but holds them sufficiently straight to permit of their being readily handled in the after operations. After quenching, the arms 9a carrying the fingers 9 are moved to the dotted line position in the

upper right-hand corner of Figure 1a, thus permitting the quenched rod to be lifted by arms 11 to a rack 12, from which the rods are supplied to a draw furnace 13. After being raised 5 in this furnace to a drawing temperature, the rods are removed through an opening 14 and supplied to the stretching machine, which is indicated diagrammatically in Figure 1c. The ends of the rod are there engaged by a fixed 10 pair of grips 15 and a movable pair of grips 16. The fixed grips are mounted on a head 17, and the movable grips are mounted on a head 18 which is movable toward and away from the head 17 by a hydraulic cylinder 28. After the 15 rods have been stretched in this machine they may be allowed to cool naturally or by a blast of air or other fluid as indicated at 20.

The machine is illustrated in more detail in Figures 2 to 6 inclusive. It comprises a pair of 20 beams 21 connected by suitable cross members to form a rigid frame. The fixed head 17 comprises a main cast body 22 supported on flanges 23 secured to the beams 21. A series of bolt holes 24 in the beams 21, and corresponding 25 bolt holes 25 in the casting 22, are provided so that the fixed head may be placed in various adjusted positions along the frame. This is to accommodate the machine to rods of different 30 nominal lengths.

30 The movable head 18 is constructed along similar lines but is carried by rollers 26 so that it can be readily moved back and forth. It is connected to the piston rod 27 of a double acting hydraulic cylinder 28 having a fluid port 29 at one end and a port 30 at the other, so that by supplying fluid to either end, as desired, the 35 head 18 may be moved toward or away from the head 17.

Each of the heads 17 and 18 is arranged to 40 accommodate the grips 15 and 16 shown in more detail in Figures 5 and 6. Each pair of grips is the same in general construction. The grip halves 15a and 16a are fixed in their respective heads while the grip halves 15b and 16b are 45 slidable therein. The latter halves are secured to slides 31 actuated by toggle links 32. The toggle links for the grip half 15b are controlled by a double-acting fluid cylinder 33 mounted on the head 17, while the corresponding links for 50 the grip half 16b are controlled by a similar fluid cylinder 34 mounted on the head 18.

The pair of grips 15 is provided with an opening 35 of the proper diameter to accommodate the body of the sucker rod S with clearance. 55 The recess 35 flares into a shoulder portion 36 which, in turn, continues as a recess 37 of enlarged diameter. Reliance is placed upon the engagement of the flared portion 36 of the grip with the shoulder on the sucker rod just inside 60 the wrench portion W for engaging the rod and stretching the same. It will be noted that the wrench portion W is not engaged at all, and that the coaxial recesses 35 and 37 by engaging the body of the rod and the box end B thereof 65 properly align the same. In like fashion the corresponding recesses in the pair of grips 16 align the pin end P of the rod with the body. These grips are more particularly described and claimed in the copending application of Frank 70 T. Cope, Serial No. 633,800, filed September 19, 1932, Patent No. 1,958,419, dated May 15, 1934.

In order to insure easy placing of the rod 75 in the grips, the shoulder portions 36 of the dies are necessarily initially somewhat closer together than are the shoulders on the rod to

be engaged. In other words, a certain amount of longitudinal clearance is necessary. This clearance and any slack in the machine (both types of lost motion are herein generally referred to as "slack") must be taken up before any stretching commences. It is then desired to stretch the rod in a predetermined amount and, in some cases, to hold the same in stretched position while it is naturally or artificially cooled. One control mechanism for effecting 10 this is shown in Figure 7.

Fluid under pressure is supplied by a positive displacement pump 38 drawing fluid from a reservoir 39 and supplying it under pressure to a pipe 40 leading to a valve 41. The purpose 15 of the valve 41 is a safety device which limits the amount of pressure supplied to the system, and is hereinafter described in greater detail. The fluid passes through the valve 41 to a pipe 42 and thence to a control valve 43 of the so-called by-passing type. It is provided with a piston 44 actuated by a hand lever 45. When the piston is in the mid position shown, fluid entering through the pipe 42 by-passes freely around the ends of the piston 44 to ports 46 and thence to a return pipe 47, leading back to the reservoir 39. If, now, the control handle 45 is moved to the right as viewed in Figure 7, the fluid passes from the valve 43 to a pipe 48 which terminates in the port 29 of the cylinder 28, thereby applying pressure to the piston and causing the head 18 to move to the right as viewed in the drawings. The handle 45 is provided with a latch 49 and fixed quadrant 50 so that it may be locked in this position. 30

The construction of the relief valve 41 is illustrated in detail in Figures 8 and 9. It comprises a body 51 having a chamber 52 therein through which the pipes 40 and 42 communicate. The upper portion of the chamber is 40 bored out as indicated at 53 to accommodate a piston 54 which is urged downwardly by a spring 55. A stem 56 projects from the bottom of the piston 54 through the chamber 52, and when the piston is in its lowermost position, substantially closes off a passage 57 communicating with a by-pass 58 leading back to the return pipe 47. A bleed 59 is provided in the piston 54 so that the fluid can pass from below the piston to above it. The fluid pressure is thus 50 communicated to a port 60 and thence to the top of a spring loaded valve 61. The spring 62 of the valve 61 is backed by a threaded plug 63 whose position may be adjusted to vary the spring pressure as desired. When the pressure 55 above the piston 54 builds up in an amount sufficient to overcome the pressure of the spring 62, the valve 61 is forced open and fluid leaks through the port 60 past the valve 61 to the valve chamber 61a and thence through a port 64 to the by-pass 58. The bleed 59 is so small that it cannot immediately equalize the pressure, and in consequence the piston 54 moves upwardly, withdrawing the stem 56 from the opening 57 and thereby allowing a certain 65 amount of the fluid from the pipe 40 to by-pass through the pipe 58 and back to the reservoir 39. The valve 41, operating in this fashion limits the pressure of the fluid supplied through the pipe 42 and thence to the cylinder 28 to a 70 figure determined by the setting of the spring 62.

When the movement of the head 18 is first initiated it takes up any slack and then begins to stretch the rod. Up to the time that stretching commences the pressure required to move 75

the head 18 will have been much less than the maximum pressure as determined by the relief valve 41. As soon as the slack is taken up, the pressure begins to build up in the cylinder 28 and the pipe 48 which supplies it. I take advantage of this fact in actuating a control mechanism which automatically defines the amount of stretching movement. A pipe 65 leads from the pipe 48 to a cylinder 66. The plunger in the cylinder is normally urged downwardly by a spring 67 of such strength that no upward movement (as the apparatus is viewed in the drawings) of the plunger occurs until the pressure in the cylinder 28 begins to build up by reason of the slack having been taken up and the stretching having commenced. At this moment the pressure of the spring 67 is overcome and the plunger of the cylinder 66 thereby forces a roller 68 carried by a head 69 against the side of a slide block 70. The slide block 70 has an opening therethrough to accommodate a rod 71 extending from the head 18. The block 70 is normally urged to the left, as illustrated in Figure 7, by a counterweight 72 connected to the block through a cable 73, this movement being limited by a rod 74 on the block 70, which rod extends through a fixed guide 75 and is provided with a stop 76. Up until the time that the roller 68 is forced against the side of the block 70, the rod 71 slides freely through the block, but when the side pressure is applied by the roller 68 the block 70 moves forward with the rod 71. In consequence the movement of the block 70 from left to right corresponds to the amount of stretch of the rod being treated. A trip 77 lies in the path of the rod 74 and is located at such distance from the end thereof as to be engaged when the desired amount of stretching has been effected. I prefer to stretch the rods in such amount that they are permanently elongated $\frac{1}{8}$ " to $\frac{1}{4}$ " per foot of length.

When the head 18 has been moved in an amount sufficient to impart the desired stretch to the sucker rod, the end of the rod 74 engages the trip 77. This releases an arm 78 which is then rotated counter-clockwise by a spring 79. The arm 78 is secured to the stem of a valve 80, and the purpose of tripping it is to effect a lowering of the pressure in the cylinder 28, thereby terminating the stretching movement while maintaining in the cylinder a sufficient pressure to hold the rod under tension while it cools. The valve 80 is connected on one side through a pipe 81 with the chamber in the relief valve 41 above the piston 54. During the stretching operation the valve 80 closes off this pipe, but when the trip 77 is actuated the spring 79 opens the valve and allows fluid to pass through the pipe 81 and the valve 80 to a pipe 82 which terminates in a relief valve 83. The relief valve 83 is constructed on the same principle as the spring loaded valve 61 but it is set to release at a lower pressure. Any fluid which is passed through the valve 83 discharges into a pipe 84 communicating with the pipe 47. Since the amount of pressure supplied to the system beyond the valve 41 is determined by the pressure above the piston 54 of such valve, and since this pressure, in turn, is determined either by the spring loading of the valve 61 or of the valve 83, it follows that when the valve 80 has established communication between the valves 41 and 83, the last mentioned valve, being set to

release at a lower pressure, will supersede the valve 61 in controlling, and the fluid pressure thereafter supplied to the system will be correspondingly reduced. The valve 83 is set to determine a pressure in the cylinder 28 sufficient to hold the sucker rod in tension but insufficient to stretch the same. When the pressure is thus reduced, the rod is maintained under a predetermined tension, and this despite contraction of the rod by cooling.

It has previously been mentioned that the grips 15 and 16 are controlled by fluid cylinders 33 and 34. Figure 7 illustrates a four-way valve 85 which controls these cylinders. Fluid under pressure such as air from any suitable source reaches the valve through a pipe 86. When the valve is in the position shown the air pressure is communicated to the pipe 87 and thence to the proper ends of the cylinders 33 and 34 to straighten the toggles 32 and close the grips 15 and 16. If the four-way valve is moved to the dotted line position, these ends of the cylinders are free to exhaust and air under pressure is supplied to a pipe 88 from which it is communicated to the opposite ends of the cylinders 33 and 34, thus opening the grips. The grips are, of course, closed when a hot rod has been placed in the machine, and the stretching operation, as above described, is then effected. After the rod has cooled the grips may be opened by actuating the four-way valve 85, and it is then only necessary to remove the stretched rod and return the parts to their original position to stretch a subsequent rod. It is desirable to set the valve 43 to mid-position, thereby releasing the tension on the rod, before the grips are opened.

In order to return the parts to their original position, the valve handle 45 is moved to the position 45a. It is held in such position by a latch 89 actuated by a spring 90 bearing against a fixed guide 91. With the valve handle in this position fluid under pressure passes from the pipe 42 through a pipe 91a to the port 30 in the cylinder 28, while the pipe 48 is free to exhaust through the four-way valve 43 to the pipe 47. This shifting of the valve causes the piston to move to the left as viewed in the drawings, thus returning the head to its original position. When this movement takes place, a rod 92 secured to the head 18 slides through an opening in one arm of the lever 78 until a nut 93 on the rod engages the lever in the last portion of the stroke of the head 18 and resets it. By this time, of course, the pressure in the cylinder 66 will have been lowered, the spring 67 will have moved the roller 68 out of contact with the block 70 and the weight 72 will have retracted the block 70 to the position shown in the drawings, thus freeing the trip 77 and permitting its spring 77a to latch it over the lever 78. At the same time an extension 94 on the rod 71 will in like manner actuate the trip 89, thus releasing the handle 45 of the valve 43, whereupon a pair of springs 95 will return the same to its normal central position.

Figure 10 shows a modified form of apparatus wherein parts corresponding to like parts in Figure 7 have been given the same reference character. This form of apparatus involves electrical connections and is of advantage in that the full sequence of operations is automatically controlled and the duties of the operator are very much simplified. In this form

of the invention the four-way valve 85 is normally urged to the dotted line position of Figure 10 by a spring 100, and in such position air pressure from the pipe 86 is communicated 5 through the valve to the pipes 88, thus holding the dies 15 and 16 in their open position. After a hot rod has been dropped into place the valve 85 is moved by the operator to the solid line position of Figure 10, thereby establishing communication 10 between the pipe 86 and the pipes 87, resulting in the dies 15 and 16 being closed. Upon such closing movement the toggles 32 close electrical contacts 101 and 102. The contact 101 is connected by a wire 103 to the line 15 wire L1. When the contacts 101 and 102 are closed, a circuit is established from L1 through the wire 103, the contact 101, a wire 104 and the contact 102 to a wire 105. The wire 105 leads to a normally closed contact 106 and 20 thence through a wire 107 to an intermediate coil 108 of a magnetic switch indicated generally by the reference character 109. The control circuit is completed through a wire 110 leading to the line wire L2. When the magnet 25 108 is energized the resistance of a spring 111 in the switch 109 is overcome and the switch arm 112 is moved from the dotted line position to the solid line position in the drawings. Current is then free to pass through a wire 113 30 and a wire 114 to the motor 115 of a so-called "thrustor" 116. These thrustors are well known articles of commerce and consist each of a small motor driven centrifugal pump built into the piston of a hydraulic cylinder and so constructed 35 as to cause movement of the piston when the pump motor is started. The circuit from the motor 115 is completed through a wire 117.

The piston of the thrustor 116 is connected 40 through a link 118 to a lever 119 having an upstanding arm 120 which is connected through a link 121 to the piston 44 of the valve 43. When the thrustor 116 is actuated the piston is moved to the right as viewed in Figure 10, 45 thereby establishing a fluid circuit from the pump 38 through the relief valve 41 and the pipe 42 to the valve 43 and thence through the pipe 48 to the cylinder 28. The valve 43 is normally urged to central position by springs 50 (not shown) corresponding to the springs 95 of Figure 7.

As in the embodiment of Figure 7, it is desired to obtain a predetermined amount of stretching after the slack has been taken up. 55 This is accomplished by the same mechanism as previously described, namely, a sliding block 70 biased in one direction by a counter-weight 72, but movable in the other direction with the rod 71 secured to the head 18 when the block 60 is forced into frictional engagement with the rod by means of the roller 68.

In this form of the invention the rod 74 which projects from the block 70 is so arranged that after the desired amount of stretching has 65 been effected it opens the contact 106 thereby breaking the circuit to the magnet 123 and allowing the spring 111 to return the switch arm 112 to its dotted line position. When this occurs current flows from the line L1 through 70 a wire 122 to a magnet 123. The magnet 123 actuates a latch 124 which releases the handle of the valve 85, thereby permitting the spring 100 to return the valve to the dotted line position and open the dies 15 and 16 releasing 75 the stretched rod. From the magnet 123 the

current flows through a wire 125 to the switch arm 112, the circuit being completed through the wires 113 and 110. The opening of the contact 106 and the consequent movement of the switch 109 breaks the circuit to the thrustor 116, thereby allowing the valve piston 44 to return to mid-position, immediately relieving the pressure in the cylinder 28 and freeing the rod of tension. 5

The opening of the grips 15 and 16 closes 10 another circuit which returns the parts to their original position. When the toggles 32 are actuated so as to open the grips they engage contacts 126 and 127. Current flows from the line L1 through a wire 128 to the switch 126, 15 thence through a wire 129 to the switch 127 and thence through a wire 130 through a normally closed contact 131. From this contact the current flows through a wire 132 to the motor 133 of a thrustor 134 and thence through 20 a wire 135 to the line L2. The thrustor 115 being out of operation at this time, the thrustor 134 serves to move the arm 120 counter-clockwise, thus moving the piston 44 of the valve 43 to the left, thereby allowing fluid under 25 pressure to flow from the valve through the pipe 91a and thence to the cylinder 28, while the other end of the cylinder is exhausted through the pipe 48, the valve 43 and the return pipe 47. When the stretching pressure is relieved, 30 the pressure in the pipe 65 is, of course, correspondingly relieved, thereby allowing the counter-weight 72 to retract the block 70 and permitting the contact 106 to close. At the end of the inward movement of the head 18, a finger 35 135 on the rod 71 opens the contact 131, thereby breaking the circuit to the motor 133 and leaving all of the parts in readiness for another operation as soon as the stretched rod has been removed and another rod put in position. It 40 will be observed that the magnet 123 is energized at this time, but as soon as the handle of the valve 85 is moved again to the solid line position it is only a moment until the grips are closed, thereby completing the circuit 45 through the magnet 108 which breaks the circuit through the magnet 123 and allows the latch 124 to function. It is therefore only necessary for the operator to periodically actuate the handle of the valve 85, the entire sequence 50 of operation being thereafter automatic.

The advantages of my invention arise from the provision of mechanism which expeditiously and automatically actuates the several parts of the stretching machine, thereby effecting rapid 55 and accurate stretching of the rods or other articles being treated.

While I have illustrated and described the present preferred embodiment of my invention and a modification thereof, it will be understood that it is not limited to the form shown but may be otherwise embodied or practiced within the scope of the following claims.

I claim:

1. A stretching machine comprising means for 65 engaging at spaced points the article to be stretched, the engaging means being relatively movable, means for applying a stretching force to an engaging means thereby to move the engaging means and stretch the article, and means 70 actuated upon stretching of the article to reduce the applied force below that required for stretching while continuing to apply sufficient force to hold the article under tension.

2. A stretching machine comprising means for 75

- engaging at spaced points the article to be stretched, the engaging means being relatively movable, means for applying force to an engaging means thereby to move the engaging means.
- 5 5. means to take up slack and thereafter stretch the article, and means effective after the slack has been taken up for defining the amount of stretching movement irrespective of the amount of slack taken up.
- 10 10. 3. A stretching machine comprising means for engaging at spaced points the article to be stretched, the engaging means being relatively movable, means for applying force to an engaging means thereby to move the engaging means.
- 15 15. means to take up slack and thereafter stretch the article, and means movable with the engaging means but only after the slack has been taken up, said means being effective for defining the amount of further movement of the engaging means.
- 20 20. 4. A stretching machine comprising means for engaging at spaced points the article to be stretched, the engaging means being relatively movable, means for applying fluid pressure to an engaging means whereby to move the engaging means and thereby stretch the article, and means actuated by the stretching movement to reduce the fluid pressure and thereby stop the stretching movement.
- 25 25. 5. A stretching machine comprising means for engaging at spaced points the article to be stretched, the engaging means being relatively movable, a fluid cylinder for effecting such relative movement, means for supplying fluid at a pressure sufficient to cause stretching of the article, and control means for reducing the fluid pressure after a predetermined amount of stretching.
- 30 30. 6. A stretching machine comprising means for engaging at spaced points the article to be stretched, the engaging means being relatively movable, a fluid cylinder for effecting such relative movement, means for supplying fluid at a pressure sufficient to cause stretching of the article, a pressure relief valve, and means for actuating the same after a predetermined amount of stretching, whereby to automatically reduce the fluid pressure.
- 35 35. 7. A stretching machine comprising means for engaging at spaced points the article to be stretched, the engaging means being relatively movable so as to take up slack and upon continued movement effect stretching of the article, a fluid cylinder for effecting such relative movement, means for supplying fluid under pressure to the cylinder so as to take up the slack and cause stretching, a pressure relief mechanism, a member associated therewith for actuating the pressure relief mechanism after a predetermined amount of movement of such member, and means for initiating movement of such member when the slack is taken up and the stretching commences.
- 40 40. 8. A stretching machine comprising means for engaging at spaced points the article to be stretched, the engaging means being relatively movable so as to take up slack and upon continued movement effect stretching of the article, a fluid cylinder for effecting such relative movement, means for supplying fluid under pressure to the cylinder so as to take up the slack and cause stretching, a pressure relief mechanism, a member associated therewith for actuating the pressure relief mechanism after a predetermined amount of movement of such member, and
- 45 45. means actuated by the increase in pressure in the system incident to the commencement of the stretching step for initiating movement of said member.
- 50 9. A stretching machine comprising means for engaging at spaced points the article to be stretched, one of such means being mounted on a movable head, means for moving the head so as to take up slack and stretch the article, and means for defining the amount of stretching movement, the last mentioned means having a control member adapted to be engaged with and moved by the head and also having means actuated upon taking up of the slack for bringing the control member into operative engagement with the head.
- 55 10. In the method of operating a stretching machine having relatively movable engaging means for holding an article to be stretched and means for effecting such relative movement, the steps consisting in supplying an article to the engaging means, effecting relative movement thereof to take up slack, continuing the movement in an amount to give a predetermined stretch, and holding the article temporarily in tension irrespective of the slack taken up.
- 60 11. In the method of operating a stretching machine having relatively movable engaging means for holding an article to be stretched and means for effecting such relative movement, the steps consisting in supplying an article while hot to the engaging means, effecting relative movement of such means to take up slack, continuing the movement in an amount to give a predetermined stretch to the article irrespective of the slack taken up, and holding the article in tension until the temperature is reduced to a desired point.
- 65 12. In the method of operating a stretching machine having relatively movable engaging means for holding an article to be stretched and fluid pressure means for effecting such relative movement, the steps consisting in supplying to the engaging means an article to be stretched, applying fluid pressure sufficient to take up the slack and stretch the article, continuing the application of such pressure for a sufficient time to impart a desired predetermined stretch to the article irrespective of the slack taken up, and then reducing the pressure so as to stop the stretching movement while maintaining the article in tension.
- 70 13. In the method of operating a stretching machine having relatively movable engaging means for holding an article to be stretched and means for effecting such relative movement, the steps consisting in supplying an article to the engaging means, effecting relative movement thereof in an amount sufficient to take up all of the slack, and continuing the movement in an amount to give a predetermined stretch to the article in addition to and irrespective of the slack taken up.
- 75 14. In the method of operating a stretching machine having relatively movable engaging means for holding an article to be stretched and means for effecting such relative movement, the steps consisting in supplying an article to the engaging means, effecting relative movement thereof to take up slack, continuing the movement in an amount to give a predetermined stretch irrespective of the slack taken up, and maintaining a predetermined tension on the article while it is cooling.
- 80 15. In the method of operating a stretching

machine having relatively movable engaging means for holding an article to be stretched and means for effecting such relative movement, the steps consisting in supplying an article to the engaging means, effecting relative movement thereof to take up slack, continuing the movement in an amount to give a predetermined stretch irrespective of the slack taken up, and holding the article under predetermined tension 10 until the temperature is reduced to a desired point.

16. In the method of operating a stretching machine having relatively movable engaging means for holding an article to be stretched and means for effecting such relative movement, the steps consisting in supplying an article to the engaging means, effecting relative movement thereof to take up slack, and continuing the movement in an amount to give a permanent 15 elongation of $\frac{1}{8}$ " to $\frac{1}{4}$ " per foot of length of the article irrespective of the slack taken up.

17. In the method of operating a stretching machine having relatively movable engaging

means for holding an article to be stretched and means for effecting such relative movement, the steps consisting in supplying an article to the engaging means, effecting relative movement thereof in an amount sufficient to take up all of the slack, and continuing the movement in an amount to give a predetermined permanent elongation to the article in addition to and irrespective of the slack taken up.

18. In the method of operating a stretching machine having relatively movable engaging means for holding an article to be stretched and means for effecting such relative movement, the steps consisting in supplying an article to the engaging means, effecting relative movement thereof in an amount sufficient to take up all of the slack, and after the slack has been taken up continuing the movement for a further predetermined distance irrespective of the movement which was required to take up slack, thereby 20 imparting a predetermined permanent elongation to the article.

ARTHUR H. VAUGHAN.

CERTIFICATE OF CORRECTION.

Patent No. 2,003,127.

May 28, 1935.

ARTHUR H. VAUGHAN.

It is hereby certified that error appears in the printed specification of the above numbered patent requiring correction as follows: Page 5, second column, line 26, claim 10, strike out the words "irrespective of the slack taken up" and insert the same after "stretch" and before the comma in line 25, of said claim; and that said Letters Patent should be read with this correction therein that the same may conform to the record of the case in the Patent Office.

Signed and sealed this 18th day of June, A. D. 1935.

Leslie Frazer
